WILLIAM C. STEWART, OF SWAMPSMOTT, MASSACHUSETTS, ASSIGNEE, BY MESNE ASSIGNMENTS, TO UNITED SHOE MACHINERY COMPANY, OF PATERSON, NEW JERSEY, A CORPORATION OF NEW JERSEY.

WORK-SUPPORT FOR BOOT AND SHOE MACHINES.

1,118,967.

Specification of Letters Patent.

Patented Dec. 1, 1914.

Original application filed November 14, 1906, Serial No. 343,458. Renewed May 3, 1913, Serial No. 765,395. Divided and this application filed July 9, 1914. Serial No. 849,926.

To all whom it may concern:

Be it known that I, WILLIAM C. STEWART, a subject of King George V of Great Britain, residing at Swampscott, county of Essex, and State of Massachusetts, have invented an Improvement in Work-Supports for Boot and Shoe Machines, of which the following description, in connection with the accompanying drawings, is a specification, like letters on the drawings representing like parts.

The invention to be hereinafter described relates to work supports for sustaining a boot or shoe in position for treatment in the manufacture of boots and shoes.

The present application is a division of application of William C. Stewart, Serial No. 343,458, filed November 14, 1906, renewal Serial No. 765,395, May 3, 1913, wherein the work support of the present invention was shown and described in connection with pulling over means.

The work support of the present invention, while well adapted for use in connection with pulling over means, as fully set forth in the application of which this is a division, is, nevertheless, not restricted thereto, but is generally adaptable for the support of a boot or shoe during its treatment by any variety of other than pulling over means. This is particularly the case where the treating means requires adjustments of the support to properly present portions of the shoe thereto, as, for instance, rights and lefts, or where the shoes or lasts on which the uppers are placed, vary in style or swing between the heel and toe. In other words, the present invention is especially useful in supporting shoes or lasts with the assembled uppers for the operation of mechanisms which require a symmetrical or other desired predetermined relation to the median lines of the adjacent end portions of the lasts or shoes presented thereto.

With these general matters in mind, an important general feature of the present invention consists in means adjustable to support shoes with the median line of one end portion of both right and left shoes in the same angular position to the right or left, and including an abutment for each end of the shoe relatively adjustable laterally for variations in crookedness of right and left

lasts. As one embodiment of this feature, the present invention contemplates a support for one end of a shoe and a support for the other end of a shoe which are relatively movable laterally about a center approximately at the ball line of the shoe and lateral movement of the other end support in the same direction.

Other features of the invention which may be conjointly or severally employed are found in the means for continuing the same directional relation of the two end supports in acting upon shoes of varying size of the same swing, and means for relatively adjusting the vertical relation of the end supports for variations in length size of the same style, or for variations in styles of the same length. These and various additional features of the invention, such as the heel end support, will best be made clear from the following description and accompanying drawings of one form or embodiment thereof for carrying the invention into practical effect, it being understood that the particulars of such form or embodiment may be varied within the true scope of the invention as defined by the claims.

In the drawings, wherein the shoe support of the present invention is illustrated as associated with the pulling over mechanism of the prior application, for convenience of exploitation, Figure 1 is a side elevation showing the shoe support with a shoe sustained in position for treatment; Fig. 2 is a longitudinal vertical section of the parts shown in Fig. 1; Fig. 3 is a plan view partly in horizontal section, showing the shoe support adjusted for sustaining a right shoe for treatment; Fig. 4 is a detail and enlarged plan view of the heel end support; Fig. 5 is a side elevation of the parts shown by Fig. 4; Fig. 6 is a rear elevation of the heel end support, the guide rods being in section; and Fig. 7 is a vertical section on the line 7—7, Fig. 4.

The supporting frame may be of any desired construction dictated by the particular means with which the shoe support is associated, but as in the parent application of which this is a division, the frame is that of a pulling over machine, the present invention may be most conveniently described in connection therewith.

The framework in this instance is provided with a suitable supporting bracket 16, Figs. 1, 2, preferably having oppositely extending portions at its top for sustaining the two end supporting members of the work support as will presently appear. On one of said extensions, preferably that which lies substantially under the instep of the last when in place upon the support, is pivotally mounted at 19, a block 18 affording a swinging sustaining member for one of the end supports. The block 18 may, if desired, be further provided with wings 21 upon which the ball of the last may rest. 15 On the other extension of the bracket 16 are preferably formed longitudinal guides 22, Figs. 2 and 3, which carry between them a sliding block 24 from which projects a standard 26 for sustaining the other end supporting member, in this instance the support or abutment for the heel end of the last. This member may be so constructed as to support, without manual adjustment, any shape of last heel, and it is convenient at 25 this time, as a matter of descriptive arrangement, to explain the preferred construction of this heel end member or abutment of the support.

The preferred construction of heel end supporting member comprises a block, in the form of a sleeve 28 keyed to the standard 26, which sleeve is provided with one or more longitudinally extending pins 30, two as here shown, slidably mounted in 35 guideways 32 in the sleeve 28 and held in normal position by means of springs 34, each spring being secured at one end to a lug on its respective pin and at its other end on the sleeve. This construction, as one convenient form, keeps the pins 30 normally and yieldingly pressed toward the other end member or abutment of the support. The pins 30 sustain a transverse block 36 forming a frame which supports by horizontally arranged pivots 38, at each end, a member 40 arranged to form a seat for the bottom and back of the heel end of the last. This construction allows the plane of the base of the heel seat to be placed at any 45 desired angle to the horizontal and to suit the style of last to be sustained by the support. The seat or rest 40 is also provided at each end with vertically arranged pins 42 to which are pivoted arms 44 adapted to 50 engage the sides of the heel portion of a shoe placed upon the seat or rest 40. These side arms 44 are normally yieldingly held against the shoe by means of a spring 46, the ends of which are secured to lugs on the arms 44. Inward movement of these arms 44 under the force of the spring 46 is limited by engagement of lugs 43 on the arms with lugs 45 on the seat or rest 40. In their preferred normal position, the arms 44 converge 55 slightly. The arms 44, and with them the

seat or rest 40, upon which they are mounted, are also yieldingly held upwardly by means of a spring 48, extending between lugs on the arms 44, and lugs on the frame 36. This upward movement is limited by engagement of 70 lugs 47 on the seat member 40 with lugs 49 upon the frame 36. In its preferred normal position, the plane of the seat or rest 40 is substantially at a right angle to the standard 26. In order to avoid marring the surface of the upper, a piece of felt 50, or other soft substance, may be secured in any convenient manner to the inner surface of the back 41 of the seat 40, and also, if desired, to the inner surface of the side arms 44. 80

The construction just described allows movement of the side arms independently of the heel for lasts of different width, and also allows a movement of the seat or rest 40 carrying the side arms with it for lasts of 85 different styles, that is, for lasts where the curve under the shank from the ball line to the heel seat may be more or less pronounced. Both these adjustments are yielding and adapt themselves naturally to the 90 heel portion of any last which may be used upon the machine. The entire heel support or abutment is also given a vertical adjustment upon its standard 26 as will be herein-after described, but from the construction 95 thus far set forth, it will be apparent that when the last with the upper thereon is placed in the machine, the arms 44 act upon the upper to slidably shape the counter to the last and hold the parts in such position 100 during the subsequent operation upon the shoe.

In positioning a last upon the machine, the heel end thereof is placed upon the seat or rest 40 and moved backward between the 105 arms 44, said arms adapting themselves to the curvature of the sides of the heel portion of the last centering the same upon its seat or rest, and conforming the heel and counter portions of the upper to the last. 110 At the same time the ball of the last is placed upon the wings 21 of the ball support, provided such wings are employed, and to further aid, among other functions, in positioning the last upon the support, a 115 toe positioning stop 52 is provided, said stop constituting one convenient form of end supporting member or abutment. This stop 52 is preferably V-shaped to better center the toe thereagainst, and is carried 120 upon one end of a link 122 which in turn, is pivoted to one end of an arm 124, pivotally mounted by its other end upon the toe block 18. The toe block 18 is provided with a transversely extending pivot pin 126 on 125 which a lever 128 is fulcrumed. One end of this lever is adapted to engage the arm 124 near its upper end but is normally kept out of engagement therewith by means of a spring 132 pressing against its other end 130

133. This spring is mounted upon a pin 134 pivoted to the lever 128 and has bearings against a collar adjacent one end of said pin, and an abutment 136 extending from the toe block 18, all as substantially set forth in the other application to which reference has been made.

From the construction described, it will be seen that by forcing the end 133 of the lever 128 against the pressure of the spring 132, the end 130 of said lever is brought into engagement with the arm 124, the movement of which about its pivot on the block 18 will force the toe stop or end support 52 toward the other or heel end support to effectively hold the last between the two said end supports or abutments, the permissible yielding movement of the pins 30 allowing heelward movement of the last as pointed out in said application. This movement of one end support or abutment toward the other as described, is preferably under control of the operative through a hand lever 138, Figs. 1 and 2, which, as here shown, is at the left hand side of the machine and is mounted on a transversely-extending rock shaft 140 carrying a cam surface 142 which, on movement of the rock shaft, is adapted to engage the end 133 of the lever 128 to force it against the tension of the spring 132 and thus bring the upper end of the lever 128 against the lever 124 and with it move the last through the end support or abutment 52, as will be readily understood. Thus, under hand manipulation, the last is engaged at its respective end portions by end supports or abutments, and is held between and by them for the action of the mechanism to which the shoe is to be subjected, and while the described characteristics of the end supports or abutments constitute a good, practical form thereof, it is to be understood that the invention may be varied in this respect to suit the conditions of use. In order that the last when thus held by the end supports or abutments shall symmetrically present the median line of one end portion of the last to the mechanism which is to treat the shoe, the present invention contemplates that the end supports shall be relatively adjustable laterally for rights and lefts, and for variations in crookedness of lasts. With respect to the toe end supports or abutments, the present invention contemplates that it shall be given a swinging movement to the right or left about a center between the end portions of the last, so that when the last is placed upon the support its toe may be correctly positioned with relation to the new location. In the particular construction herein illustrated and as fully described in the application of which this is a division, this may be accomplished by means now to be described.

The toe block 18, which carries the ball supports 21 and a toe positioning stop 52, is pivoted at 19 on the extension of the bracket 16, the pivot lying upon the center line of the machine, and a curved gib 17 is mounted upon the bracket 16 in position to guide the end of the toe block. The toe block 18 is also provided with a tail piece 442, which preferably has a forked end, Figs. 2 and 3, adapted to engage a pin carried by an arm 445 projecting rearwardly from the inner end of the arm 414 which carries the beveled segment 415 meshing with a corresponding segment 413, Fig. 3, on the arm 412, Fig. 2, which rises from the rock shaft 410. A hand lever 408 effects swinging movement of the arm 414 through the connections stated and as fully described in said other application.

From the construction described, it will be readily seen that as the lever 408 is moved in one direction it will throw the tail piece 442 of the toe block 18 to the right of the center line of the machine, and consequently the toe positioning stop 52, which is on the opposite side of the pivot 19 from the tail piece 442, will be thrown to the left of the center line of the machine. Similarly, a movement of the lever 408 in the other direction will throw the toe positioning stop 52 to the right of the center line of the machine, thereby positioning the end portion of the last with its median line of right or left lasts symmetrically disposed with respect to the means to the treatment of which the shoe is to be subjected.

Coincident with the movement of the toe end support or abutment for rights and lefts, or for the particular swing of the last, the present invention further contemplates that the other end support or abutment shall be appropriately moved laterally to properly position such other end support or abutment to the change in the swing of the last. Likewise, for the treatment of shoes of different lengths, the distance between the two end supports or abutments is to be changed; and the present invention, therefore, contemplates that in such changing relations the direction of movement of the heel end support or abutment shall continue in the direction prescribed by the swing of the last. Adjustment for variations in lengths of lasts may be appropriately described first. The means preferred to perform this adjusting operation for variations in length, is best indicated in Figs. 1 and 3, wherein a short shaft 478 is suitably journaled at one side on the frame of the machine, and is rocked through a lever 480 secured thereto, said shaft also being provided with an arm 482 having a beveled gear segment 483 which meshes with a second beveled gear segment 485 which may be carried by one end of a link 484 pivoted at 486 between its

ends to a stationary bracket. A similar link 488 is pivoted at its outer end to a stationary bracket 489 and the inner ends of these two links are pivoted together by means of 5 a pin 490, they being of sufficient length to form a toggle joint extending transversely of the support. The pin 490 has also connected to it one end of a link 492, Figs. 2 and 3, extending longitudinally of the machine, its outer end being pivoted to the heel block 24.

By means of the connections just described, it is seen that upon movement of the lever 480 in one direction through the 15 toggles 484 and 488, the heel block 24, sustaining the heel end support or abutment, is moved in its guides 22. This movement of the heel block 24 in one direction will increase the distance between the toe end support or abutment 52 and the back 41 of the heel end support, and movement in the other direction will act in the reverse manner.

Owing to the fact that it is desirable, in this embodiment of the invention, to keep 25 the toe ends of all sizes of right lasts of a prescribed swing in a single initial position longitudinally, and the toe ends of all left lasts of the same character in an analogous single initial position, and further, owing to 30 the fact that when so positioned the heel end of a right last must have a deflection or swing to the left and the heel end of a left last must have a swing or deflection to the right as the standard 26 is moved to increase or decrease the distance between the 35 two end supports, the heel end support should be guided in a line having the same angular relation to the longitudinal center line of the machine as the swing of the last to be supported. To this end, the arm 414 is provided with a projecting slotted member 500, Figs. 2 and 3, the end of the slot being preferably directly above the pivot pin 416 of said arm 414. The heel end supporting standard 26 is directly sustained by 45 a block 502, movable transversely in guideways 504, Fig. 2, formed in the heel block 24, and the lower end of the heel end supporting standard 26 extends through the 50 sustaining block 502 and through a transverse slot 25, Fig. 3, in the heel block 24. This standard carries at its lower end, a roll 506 adapted to rest in the slot formed in the member 500. From the construction described, it will be seen that when the lever 408 is moved to throw the toe end support or abutment to the left of the center line of the machine, in positioning the toe of a right last, the slotted member 500 will also 55 be thrown to the left hand side of the center line of the machine about the pivot 416, thus taking the position having substantially the same angular relation to the center line as the swing of the heel of the last to be supported, see Fig. 3. When the controlling 60

lever 480 is thereafter moved to adjust the machine for a larger size of last and the heel block 24 is moved in a line parallel to the center line of the machine in its guides 22, the heel end supporting standard 26 is 70 guided in its movement by the slotted member 500, being carried to one side of the center line as it is thus moved, the transverse movement being allowed by the transverse slot 25, Fig. 3, in the heel block 24 and 75 the movable block 502. By the means described, the heel end support or abutment is always placed in correct relation to the toe end support or abutment, no matter what size shoe is to be treated, whether right or 80 left.

It is desirable in some treatment, to support the last with its ball resting firmly upon the wings 21 which act as a ball support, though these are not always essential. With 85 different sizes of lasts, the curvature under the shank from the ball line to the heel will vary, and therefore the vertical distance between the plane of the ball of the last and the plane of the heel seat or rest will vary. 90 This distance will also vary with different styles of lasts of the same size. To insure the positioning of the last as desired, the present invention contemplates means for varying the vertical distance between the 95 ball support and the heel seat or rest 40, and to this end the heel end support is made adjustable upon its standard as is best illustrated in Figs. 1 and 2. As there shown, the sleeve 28, which carries the entire heel end 100 support, is given a free motion vertically on the standard 26 and is provided with an arm 530 on which is a roll 532. This roll rides within a slot 534 of a bar 536 extending longitudinally of the machine, and suitably 105 supported upon the machine frame as by the standards 538. Each end of the bar 536 has a slotted connection 540 with its respective standard so that the angular relation of the bar to the heel standard 26 may be altered 110 at will in conformity with different styles or kinds of lasts.

With the construction described, as the heel standard is moved in either direction by the lever 480, to adjust the heel end support 115 or abutment for a different size of last, the roll 532 travels up or down the slot 534, and the heel end support or abutment will be raised or lowered as it moves longitudinally. The variation in the distance between the 120 planes of the ball and heel rest of a last for each difference in size, is constant for any particular style, and therefore by changing the angle of the bar 536 it will automatically and correctly vary the height of the heel rest 125 or seat member 40 with respect to the toe end support for any style of last when the machine is adjusted for size.

The right and left controlling lever 408 is provided with means to lock it in one posi. 130

tion or the other, and it is desirable to make such means adjustable so that the throw of the lever may be readily altered to correctly set the parts to position different styles of shoes or crooked lasts. The preferred construction for use with this particular embodiment of the invention is best shown by Fig. 3, wherein there is mounted on the journal of the rock shaft 410, a bracket 592, Figs. 1 and 2, having a segment top 593, Fig. 3. This segment is channeled longitudinally, and in the channel are two blocks 594, each provided with a beveled projection 596 and a shoulder 598 forming between them a recess. The shank of the controlling lever has mounted therein a spring-pressed detent 600 which, when the lever is moved, will ride up one or the other of the beveled projections 596 and seat itself in one of the recesses, thus locking the lever in the position to which it is thrown. In order to alter the amount of throw, the blocks 594 are made adjustable on the segment 593. The segment top is provided with a slot 602 at each end and the blocks 594 are held at any desired point in their respective slots by the clamping screws 604.

The size controlling lever 480 is provided with a suitable locking means and scale to aid the operative in quickly setting the machine. Referring to Fig. 1: a bracket 608 is mounted on the journal of the rock shaft 478. This bracket sustains a segment 610 provided with teeth adapted to be engaged by a spring-pressed detent 612 carried by the shank and the lever 480. The segment is also preferably provided with a scale to indicate the proper amount of movement to be given to the lever 480 to set the machine for the required size of shoe. Frequently a given size of one style of shoe will be equal to a quarter or half size larger or smaller than the same given size of another style, and it is therefore desirable to provide means for adjusting the scale with relation to the controlling lever so that the figures on the scale denoting a particular size may be used with a new standard of measurement. To this end there is preferably provided a guide-way for the segment 610 on the bracket 608, for instance, a mortise and tenon, 614, and a clamping screw 616 is passed through the segment and through the slot in the bracket. The scale is thus easily adjusted for different standards of size.

As will be evident from the described embodiment of the invention, the work support sustains the shoe sole downward with the forepart of the sole resting on a support and the heel portion sustained in desired relation thereto as prescribed by the curvature between the ball line and heel, the construction being such that the shoe is presented to the machine for treatment in the most convenient position for the operative

to determine the relation of the upper and last. This is important in some operations to which the shoe is subjected, and other features of the invention are well adapted for use in connection therewith, but such other features, as will be readily understood, and not confined to such association. It will also be evident that the shoe support of the present invention positions the median line of the toe end of right and left shoes in corresponding angular relation with the center line of the machine, the toe end support or abutment being movable laterally in a curved path about a center between the two supports while the heel end support is movable laterally in the same direction and in a straight path. The two end supports having been appropriately adjusted for any swing of last, it will be noted that the angular relation of the median line of the shoe to the center line of the machine will be continued or maintained as different lengths of shoes are placed upon the support for treatment. This is of importance, because, as well understood by those skilled in the art, some machines require that one end of the shoe shall be presented in a defined or predetermined position even though the length of the shoes may vary, and this same requirement exists in some cases even though the style of shoe, or the curvature thereof at the shank may change in the different shoes treated, all of which find response in the various features of the invention as hereinbefore described.

The terms "last" and "shoe" are herein used in the general sense and are intended to indicate that the shoe upper and last are in assembled relation.

What is claimed is:—

1. In a work support for boot and shoe machines, the combination of a toe end supporting member, and a heel end supporting member constructed and arranged to support a shoe between them, said heel end supporting member being laterally movable to accommodate itself to lasts of different swing and constructed for engaging the counter portion of an upper on a last to conform the rear portion of the upper including the counter to the last by a sliding shaping movement relative to the last and upper.

2. In a work support for boot and shoe machines, the combination of a support for one end of a shoe and a support for the other end of the shoe constructed and arranged for relative movement laterally one about a center located between the ends of the shoe and the other in a rectilinear path.

3. A work support for boot and shoe machines, comprising an end support or abutment for one end of a shoe, an end support or abutment for the other end of the shoe, means for adjusting the relative lateral po-

- sitions of said end supports to maintain like angular relations of the median lines of right and left shoes to the center line of the machine, and means for continuing the 5 established angular relation of an end support during the adjustment of said support for variations in sizes of shoes by movement of said support in the direction of the established angular relation.
- 10 4. A work support for boot and shoe machines, comprising an end support or abutment for one end of a shoe, and an end support or abutment for the other end of the shoe, said end supports or abutments being 15 relatively adjustable laterally to position right and left shoes with the median line of one end portion in corresponding angular relation to the center line of the machine, the end support or abutment for so positioning 20 the median line of one end portion of the shoe being laterally movable about a center substantially opposite the ball line of the shoe.
- 25 5. A work support for boot and shoe machines, comprising an end support or abutment for one end of a shoe, and an end support or abutment for the other end of the shoe, said end supports or abutments being 30 relatively adjustable laterally to position right and left shoes with the median line of one end portion in corresponding angular relation to the center line of the machine, the end support or abutment for so positioning 35 the median line of one end portion of the shoe being laterally movable about a center substantially opposite the ball line of the shoe, the other end support or abutment being laterally movable in a straight path.
- 40 6. In a work support for boot and shoe machines, the combination of an end support or abutment for one end of a shoe, an end support or abutment for the other end of the shoe, one of said end supports or abutments being movable in a curvilinear 45 path about a center located between said end supports or abutments, the other being laterally movable in a straight path, and means for effecting simultaneous lateral movements of said supports for rights and lefts.
- 50 7. In a work support for boot and shoe machines, the combination of an end support or abutment for one end of a shoe, an end support or abutment for the other end of the shoe, one of said end supports or abutments being movable in a curvilinear 55 path about a center located between said end supports or abutments, the other being laterally movable in a straight path, and means for effecting simultaneous lateral 60 movements of said supports for rights and lefts and maintaining the same angular relation of the median lines of said end supports or abutments to the center line of the 65 machine as said end supports or abutments

are adjusted for variations in lengths of right and left shoes.

8. In a work support for boot and shoe machines, the combination of a support for one end of a shoe, a support for the other end of the shoe, and means for laterally moving one of said end supports in a curvilinear path and simultaneously moving the other end support laterally in a straight path. 75

9. In a work support for boot and shoe machines, the combination of a support for one end of a shoe, a support for the other end of the shoe, and means for laterally moving one of said end supports in a curvilinear path and simultaneously moving the other end support laterally in a straight 80 path and maintaining the established angular relations of the median lines of the end supports as they are adjusted for variations in shoe length. 85

10. In a work support for boot and shoe machines, the combination of an end support for one end of a shoe, an end support for the other end of the shoe, said supports being relatively movable simultaneously laterally to correspondingly position right and left shoes with the median line of one end portion in the same angular relation with the center line of the machine, and means 95 for changing the vertical relation of said end supports for variations in styles.

11. In a work support for boot and shoe machines, the combination of an end support for one end of a shoe, an end support for the other end of the shoe, said supports being relatively movable laterally to correspondingly position right and left shoes with the median line of one end portion in the same angular relation with the center 100 line of the machine, means for changing the vertical relation of said end supports for variations in styles, and means for automatically changing the vertical relation of the end supports as they are adjusted toward 105 and from each other for variation in shoe length. 110

12. In a work support for boot and shoe machines, the combination of a support for one end of a shoe, a support for the other end of the shoe, means for relatively moving said end supports into position to support different sized shoes, and means for guiding an end support during its movement in a direction at an angle to the machine center 115 line. 120

13. In a work support for boot and shoe machines, an end support for one end of a shoe, an end support for the other end of the shoe, means for relatively moving said supports into position to receive shoes of different sizes, and means for guiding one of said end supports laterally in the direction of the swing of the shoe during such movement. 125

14. In a work support for boot and shoe 130

- machines, a support for one end of a shoe, a support for the other end of the shoe, means for moving said supports into relative position to support different sized shoes, means for guiding one of said end supports laterally in the direction of swing of the shoe during such movement, and means for adjusting said guiding means into positions for rights and lefts. 5
- 10 15. In a work support for boot and shoe machines, an end support or abutment for one end of a shoe and an end support or abutment for the other end of the shoe, said end supports or abutments being constructed and arranged to have united movement laterally in the same direction, the one in a curved and the other in a straight path, to positions for supporting right and left shoes, and relative movement longitudinally. 15
- 20 16. In a work support for boot and shoe machines, a toe end support, a heel end support, means for adjusting said two supports laterally in the same direction with relation to the center line of the machine for rights and lefts, and means for further adjusting one of said end supports laterally as it is moved for accommodating shoes of different lengths. 25
- 25 17. In a work support for boot and shoe machines, the combination of means for sustaining a shoe including a longitudinally and vertically adjustable shoe end support, a slotted member angularly arranged with relation to the longitudinal path of adjusting movement, and means disposed between said end support and slotted member whereby movement of the end support longitudinally will also move it vertically. 30
- 30 18. In a work support for boot and shoe machines, the combination of means for sustaining a shoe including a longitudinally and vertically adjustable shoe end support, a slotted member angularly arranged with relation to the longitudinal path of adjusting movements, means disposed between said end support and slotted member whereby movement of the end support longitudinally will also move it vertically, and means for adjusting the angle of said slotted member. 35
- 40 19. In a work support for boot and shoe machines, a heel end support comprising a heel seat or rest and shoe engaging arms, said parts being constructed and arranged to have united movement in one direction and relative movement in another direction. 50
- 45 20. In a work support for boot and shoe machines, a heel end support comprising a heel seat or rest and shoe engaging arms, said parts being constructed and arranged to have united movement in one direction and relative movement in another direction, and means for limiting the movement in either direction. 55
- 50 21. In a work support for boot and shoe machines, a standard, and a heel end support mounted thereon constructed and arranged to have movement longitudinally, transversely, and about a transverse pivot with relation to said standard. 60
- 55 22. In a work support for boot and shoe machines, a standard, and a heel end support mounted thereon constructed and arranged to have movement longitudinally, transversely, and about a transverse pivot with relation to said standard, at least one of said movements being yielding. 65
- 60 23. In a work support for boot and shoe machines, the combination of a support for one end of a shoe, a support for the other end of the shoe, means for simultaneously moving said supports laterally to position them to the swing of the shoe, and means for guiding the lateral movement of one of said supports in a straight path and the other in a curvilinear path in the same direction. 70
- 65 24. In a work support for boot and shoe machines, the combination of a support for one end of a shoe, a support for the other end of the shoe, means for simultaneously moving said supports laterally to position them to the swing of the shoe, means for guiding the lateral movement of one of said supports in a straight path and the other in a curvilinear path in the same direction, and means for maintaining the angular relation of the median lines of the shoe to the center line of the machine as the said supports are adjusted for different sized shoes of the same style. 75
- 70 25. A work support for boot and shoe machines, comprising a heel sustaining frame, a heel seat mounted on said frame for movement in one direction and shoe engaging arms mounted on said heel seat for movement in another direction. 80
- 75 26. In a work support for boot and shoe machines, a heel support comprising a frame, a heel seat yieldingly pivoted on said frame, and shoe engaging arms yieldingly pivoted on said heel seat. 85
- 80 27. In a boot and shoe machine, a heel support comprising a frame, a heel seat movably mounted on said frame, and yieldingly connected shoe engaging arms separately mounted on said heel seat. 90
- 85 28. In a work support for boot and shoe machines, a standard, a block mounted for longitudinal movement on said standard, a frame mounted in said block for transverse movement with relation to said standard, and a heel seat mounted on said frame for pivotal movement with relation to said standard. 95
- 90 29. In a work support for boot and shoe machines, the combination of a heel end support, a support engaging the ball of the shoe, said supports being constructed and arranged to support the shoe sole downward, and means acting through the heel end sup- 100

port for maintaining the established relation of the ball support with the forepart of the shoe for differently shaped shoes.

30. In a work support for boot and shoe machines, the combination of a toe end engaging means, and heel part engaging means, means to relatively move them to engage a shoe therebetween, and means for moving the toe end and heel part engaging means laterally in the same direction for right and left shoes, and means for directing the lateral movement of one of said end engaging means in a straight path.

31. A work support for boot and shoe machines, having in combination, shoe positioning means comprising a toe end engaging member and a heel part engaging member, means normally acting in a direction to cause relative approach of said members, and means for adjusting said members transversely in the same direction in accordance with the swing of the last.

32. A work support for boot and shoe machines having a heel support comprising shoe engaging arms, said arms being constructed

to have united movement in two directions for adjustment to lasts of different sizes and swing, and relative movement to receive the heel portion of a shoe between them.

33. In a work support for boot and shoe machines, toe end engaging means and heel end engaging means constructed and arranged to receive and support a shoe between them, said heel end engaging means being constructed and arranged to act upon the counter portion of the upper to conform the rear portion of the upper to the last by a sliding shaping movement as the last and upper are placed in the support, and means for moving the toe end and heel portion engaging means laterally in accordance with the swing of the last.

In testimony whereof, I have signed my name to this specification, in the presence of two subscribing witnesses.

WILLIAM C. STEWART.
